Patented Dec. 9, 1924.

UNITED STATES PATENT OFFICE.

MOSES S. OKUN, OF PHILADELPHIA, PENNSYLVANIA.

PROPELLER.

Application filed December 30, 1918, Serial No. 263,202. Renewed March 18, 1924.

To all whom it may concern:

Be it known that I, MOSES S. OKUN, a citizen of the United States, residing at 670 North 12th Street, Philadelphia, in the county of Philadelphia and State of Pennsylvania, have invented certain new and useful Improvements in Propellers, of which the following is a specification.

The object of my invention is to construct a simple and cheap propeller for the propulsion of marine or air vessels or of any other device for transportation.

It is further the object of my invention to construct a propeller which will have a very high efficiency and which will retain its high efficiency at different speeds of the vessel, so that the speed of the said vessel could be varied without affecting very much the efficiency of the propeller.

In order to attain such results, I employ a body, which is mounted on a shaft and which rotates with the same. Said body is provided with means to set water or air into rotary motion. I also employ means in my invention which utilize the centrifugal force developed from the rotation of the said air or water to create a pressure upon said body, which is transmitted longitudinally to the axis of the shaft and to the vessel.

With these and other objects in view, my invention consists in novel and peculiar arrangements and combinations of several parts of the apparatus—all as hereinafter fully described in the specifications and then pointed out in the claims.

My invention is illustrated in the accompanying drawings in which Fig. 1 shows the front view of my propeller, Fig. 2 represents the same view without the cover or ring 9. Fig. 3 is a longitudinal sectional view of my invention. Figs. 4, 5, 6 represent axial sectional views of different modifications of my invention.

Similar numbers refer to similar parts throughout all views.

1 is a casing, which is mounted by the blades 2, 2, on the enlarged portion of the main shaft 7. The casing 1 is provided with the covers 9 and 9^a (Fig. 3); 5, 5 are openings in the covers 9 and 9^a through which water or air enters into the casing 1. The cover 9 is of a smaller diameter than the diameter of the casing and the space between outer walls of the said casing and the cover 9 serves as an outlet for the water or air

drawn in through the openings 5, 5. The long vanes or blades 2, 2, and the short vanes 3, 3, divide the inside chamber of the casing 1 in compartments, into which water or air is forced through the openings 5, 5; said water or air, being set into rotary motion by the blades 2, 2, and 3, 3, is discharged from the casing 1 by the action of centrifugal force through the openings 4^a, 4^a.

10^b, 10^a, 10^e are funnel-shaped screens or shields which are preferably fastened to the casing, so as to rotate with the same. Such screens or shields act as receivers for the water or air discharged from the casing.

The said water or air, after being discharged from the casing, still continues its rotary motion in the direction of the motion of the casing and the screens 10^b.

The centrifugal force of the rotating water or air produces a pressure upon the screen or shield, which is transmitted to the vessel or vehicle in the direction of the motion of the same.

The shaft 7 with the propeller attached to the same is set in motion by any power delivery device, such as steam, gas, electric or any other engine.

Water or air is drawn in through the openings 5, 5, and through the compartments or channels 4, 4, and is discharged from the casing through openings 4^a, 4^a.

The action of the centrifugal force of the rotating water or air produces a pressure upon the walls of casing 1. The cross-sectional area of the cover 9^a is greater than that of the cover 9, and therefore we will have a difference of pressure upon the cover 9^a which will be transmitted to vessel or vehicle in the direction of the motion of the same. In order to absorb the mechanical energy of the water or of the air after the same is discharged from the casing 1, the screens 10^b, 10^a, 10^e are used.

These screens are funnel-shaped and are turned with their narrow end in the direction of the motion of the vessel or vehicle.

The centrifugal force of the water or of the air which rotates with the screens produces a pressure upon said screens which is also transmitted to the vessel or vehicle in the direction of the motion of the same.

Figs. 4, 5, 6 represent different forms of

screens. Fig. 4 represents a screen of conical shape. Fig. 6 is of curved shape. Fig. 5 of conical and curved shape.

I wish to be understood as not limiting 5 my invention to the precise forms of construction herein set forth, as various modifications may be made in the different parts thereof without, however, departing from the spirit of my invention.

10 Having thus described my invention, what I claim and desire to secure by Letters Patent is:—

15 1. A propeller comprising a body mounted upon a shaft and adapted to rotate with the same, said body having means to set water or air into rotary motion, a funnel-shaped screen or shield into which the rotating water or air is discharged from the said means; said funnel-shaped screen or shield 20 being located so as to have its narrow end turned in the direction of the motion of the vessel or vehicle.

25 2. A propeller comprising a body mounted upon a shaft and adapted to rotate with the same, said body having means to set water or air into rotary motion, a funnel-shaped screen or shield attached with its narrow end to said rotating body and adapted to receive the rotating water or air which 30 is set in motion by the said rotating body.

35 3. A propeller comprising a casing mounted upon a shaft and adapted to rotate with the same, said casing having means to draw in water or air and to set the same in rotary motion; an opening or openings in one side of the casing to discharge the water or air from the same in the direction opposite to the direction of the motion of the vessel or vehicle, a funnel-shaped screen or 40 shield attached with its narrow side to the casing to receive the rotating water or air discharged from the said casing.

4. A propeller comprising a casing mounted upon a shaft and adapted to rotate with the same, an inlet for water or air in the 45 said casing, blades or vanes provided in the same to set the water or air into rotary motion, an outlet in one of the sides of the casing to discharge the said water or air in the direction opposite to the direction of movement of the vessel or vehicle, a funnel-shaped screen or shield attached with its narrow side to the casing to receive the rotating water or air discharged from the said 50 blades.

5. A propeller comprising a shaft, blades or vanes mounted upon said shaft and which rotate with the same, said blades or vanes being adapted to set water or air in rotary motion, a funnel-shaped screen or shield to 60 which the rotating water or air is directed so as to produce a pressure upon the said screen or shield by the centrifugal force of the said rotating water or air, and means to transmit said pressure to the vessel or vehicle.

6. A propeller comprising a shaft, blades or vanes mounted upon said shaft and which rotate with the same, said blades or vanes being adapted to set water or air into rotary 70 motion, a funnel-shaped screen or shield attached to the blades and upon which the rotating water or air is directed so as to produce a pressure upon said screen or shield, which is transmitted to the shaft in the direction of the movement of the vessel or vehicle.

In testimony whereof I affix my signature in the presence of two witnesses.

MOSES S. OKUN.
